UNITED STATES PATENT OFFICE.

ROBERT B. GREENWAY, OF SAN BERNARDINO, CALIFORNIA.

GREASE-CUP.

1,172,020.

Specification of Letters Patent. Patented Feb. 15, 1916.

Application filed November 3, 1915. Serial No. 59,422.

To all whom it may concern:

Be it known that I, ROBERT B. GREENWAY, a citizen of the United States, residing at San Bernardino, in the county of San Bernardino and State of California, have invented a certain new and useful Improvement in Grease-Cups, of which the following is a specification.

My invention relates to improvements in grease cups.

It relates particularly to grease cups of a type having an outer shell adapted to be secured to a moving part of machinery, such as the side rod of a locomotive, the shell having fitted in it a bushing in which is mounted a screw plug for forcing the grease from the shell into a bearing.

In my copending application, Number 21,516, filed April 15, 1915, there is shown and described a grease cup of this general type, in which the lower end of the plug is closed, thus limiting the quantity of grease which may be placed into the cup to the capacity of the outer shell.

One of the objects of my present invention is to provide a construction having a hollow plug open at the inner end, whereby the capacity of the grease cup will be relatively greater than in my other invention above referred to. In my said other invention, a spring secured to the outer shell releasably held the plug from turning in either direction. This construction requires that the spring be withdrawn from engagement from the plug when the plug is screwed inwardly.

One of the objects of my present invention is to provide a construction which will permit the plug to be screwed inwardly without releasing the spring from engagement therewith, and which will hold the plug from being accidentally screwed outwardly.

The novel features of my invention are hereinafter fully described and claimed.

In the accompanying drawing, which illustrates my invention, Figure 1 is a vertical sectional view of my improved grease cup shown mounted in the side rod of a locomotive, the side rod and parts connected therewith being shown partly in section and partly in side elevation. Fig. 2 is a side elevation of the grease cup and a portion of the side rod, shown enlarged. Fig. 3 is a top view of the grease cup shown in Figs. 1 and 2, the spring being shown released from the plug. Fig. 4 is a top view of the same

showing the spring engaged with the plug. Fig. 5 is a fragmental side elevation of the grease cup. Fig. 6 is a cross section on the line 6—6 of Fig. 5. Fig. 7 is a top view of a modified form of plug.

Similar reference characters designate similar parts in the different views.

1 designates an outer shell having a screw threaded upper end in which is fitted an internally and externally threaded bushing 2 in which is fitted an externally threaded plug 3 which is hollow, and which has an open inner end and a closed outer end. The plug is, preferably, provided with a polygonal upper end adapted to be gripped with a wrench. The lower end of the outer shell 1 may be secured in any desired manner, as by brazing, to a part of the machinery, such as a locomotive side rod 4, with which the grease cup is to be used.

In the drawing the side rod 4 is shown mounted on a bushing 5, which is mounted on a crank pin 6. A hole 7 extends through the bushing 5 and the upper portion of the side rod 4 and communicates with the interior of the outer shell 1. By turning the plug 3 in the proper direction it may be screwed inwardly so as to force grease carried in the shell 1 through the hole 7 and upon the crank pin 6.

For preventing accidental turning of the bushing 2 in the shell 1, and to prevent the plug 3 from accidentally unscrewing owing to the vibration of the moving parts, I provide releasable means for locking the bushing 2 to the shell 1, said means also providing for releasably locking the plug 3 from turning in one direction, while permitting it to be readily turned in the opposite direction. For effecting these functions the following described mechanism may be employed, see Figs. 1 to 6 inclusive: 8 designates an arcuate spring having one end secured, as by rivets 9 to the periphery of the shell 1. The other end of the spring 8 extends through a transverse slot 10 in the upper end of the bushing 2, and is adapted to enter any one of one or more longitudinal grooves provided in the periphery of the plug 3 and designated by 11. The spring when in any one of the grooves 11 will hold the plug from screwing outwardly, but, by reason of the free end of the spring having a beveled portion 12 adapted to be struck by one wall of a groove 11, the plug may be readily screwed inwardly without having to

withdraw the spring 8. The grooves 11 do not extend to the lower end of the plug 3. For withdrawing the spring 8 from engagement with the plug 3, when it is desired to 5 remove the plug for the insertion of grease into the shell 1, there is provided a lever 13 having its fulcrumed end rounded and pivotally fitted in a peripheral recess 14 in the bushing 2. The spring 8 extends through a 10 hole 15 in the lever 13, the outer side of the fulcrumed portion of which is provided with a notch 16 adapted to receive the spring 8 when the lever is in the locking position, as 15 shown in Fig. 4. When in this position, the spring 8 holds the lever 13 in the closed or locking position.

In Fig. 7 I have shown a modification of the plug. In this form, the plug 3' is provided with a plurality of longitudinal 20 ratchet grooves 11', which permit the plug to be freely screwed inwardly but which prevent its being accidentally unscrewed. In other respects the plug 3' corresponds in construction to the plug 3. When the grease 25 cup is to be filled, the lever 13 is swung to the position shown in Fig. 3, thus releasing the spring 8 from the plug 3. The plug may now be unscrewed from the bushing 2. The plug and shell 1 may now be filled with 30 grease and the plug replaced in the bushing 2, the lever 13 being then swung to the position shown in Fig. 4, thereby permitting the spring 8 to reengage the plug. From time to time the plug is screwed inwardly so as 35 to force grease through the hole 7 into the bearing. This may be effected without releasing the spring 8 or operating the lever 13. Vibration or pounding of the parts will not cause the plug or bushing 2 to unscrew. 40 In case the grease has all been forced from the shell 1 and the bearing becomes heated from lack of lubrication, the plug 3 will be heated so as to melt the grease contained 45 therein and this grease will run from the plug into the bearing and will afford the lubrication needed. Thus by having an extra supply of grease carried in the plug, damage to the parts, due to lack of proper attention on the part of the operator, may 50 be avoided.

I do not limit my invention to the structure shown and described, as modifications, within the scope of the appended claims, may be made without departing from the 55 spirit of my invention.

What I claim is:—

1. In a grease cup, an outer shell, a bushing having threaded engagement therewith, a hollow plug open at its inner end and 60 closed at its outer end and having threaded engagement with the bushing, and means secured to the outer shell for releasably holding the bushing and plug from turning.

2. In a grease cup, an outer shell, a bush- 65 ing having threaded engagement therewith,

a hollow plug open at its inner end and closed at its outer end and having threaded engagement with the bushing, and a spring secured to the outer shell and having means for releasably engaging the bushing and plug for holding them from turning.

3. In a grease cup, an outer shell, a bushing having threaded engagement therewith and provided with a slot, a hollow plug open at its inner end and closed at its outer end and having threaded engagement with the bushing, and a locking member secured to the outer shell and extending into said slot and adapted to releasably engage said plug.

4. In a grease cup, an outer shell, a bushing having threaded engagement therewith and provided with a slot, a hollow plug open at its inner end and closed at its outer end and having threaded engagement with the bushing, and a spring secured to the outer shell and extending into said slot and adapted to releasably engage said plug so as to hold it from turning in one direction.

5. In a grease cup, an outer shell, a bushing having threaded engagement therewith, a plug having threaded engagement with the bushing, and means secured to the outer shell for releasably holding the bushing from turning, and provided with a ratchet connection with the plug which will permit the plug to turn in one direction and will releasably hold it from turning in the opposite direction.

6. In a grease cup, an outer shell, a bushing having threaded engagement therewith, a plug having threaded engagement with the bushing, and a spring having means for releasably holding the bushing from turning and secured to the outer shell and provided with a releasable ratchet connection with the plug which will permit the plug to turn in one direction and will releasably hold it from turning in the opposite direction.

7. In a grease cup, an outer shell, a bushing having threaded engagement therewith, a plug having threaded engagement with the bushing, and provided with a longitudinal peripheral groove, and a spring secured to the outer shell and releasably engaging said bushing and adapted to engage with said plug in said groove, the engagement of the spring with the plug being such as will permit the plug to turn in one direction and will releasably hold it from turning in the opposite direction.

8. In a grease cup, an outer shell, a bushing having threaded engagement therewith, a hollow plug having threaded engagement with the bushing, and means secured to the outer shell for releasably holding the bushing from turning and adapted to have ratchet connection with the plug which will

permit the plug to turn in one direction and will releasably hold it from turning in the opposite direction.

9. In a grease cup, an outer shell, a bushing having threaded engagement therewith, a hollow plug having threaded engagement with the bushing and provided with a longitudinal peripheral groove, and a locking member secured to the outer shell and hav-

ing means for releasably holding the bushing from turning, and being movable into and out of said groove and adapted to releasably hold said plug from turning in one direction.

In testimony whereof I have signed my name to this specification.

ROBERT B. GREENWAY.
